[57] ABSTRACT

A circuit breaker wherein electrical arrangement for detecting excess current in and switching or breaking power supply contacts for associated circuit and mechanical arrangement for transmitting ON-OFF operation or contact switching operation to the contacts are separately disposed as electrically insulated by a separation wall in a chassis for integrally housing the both arrangements. The separation wall has only two narrow apertures for allowing the motion responsive to detected excess current transmitted to the mechanical arrangement and therethrough back to the contacts.

CIRCUIT BREAKER

This invention relates to a circuit breaker for protecting a load by breaking a circuit in case such excess current as a short-circuiting current or overload current flows through the circuit.

Generally a circuit breaker is formed largely of three parts of an operating part, switching contact part and excess current detecting part so that, in case an excess current flows through a circuit, this excess current will be detected by the excess current detecting part and the switching contact part will be operated, through the operating part, by this detection to switch off the circuit. The above mentioned three parts have been arranged and fixed on the same surface (for example, the upper surface) of a chassis made of a synthetic resin. However, the operating part is mostly of a mechanical formation while the switching contact part and excess current operated element are mostly of electric formations. Therefore, there have been defects that, when they are fixed as arranged on the same surface of the chassis, the assembling work specifically in the mechanical field must be carried out with a larger attention than is required to the electric parts outside the mechanical field and is, therefore, inefficient and that, in the case of the maintenance and inspection, the mechanical part and electrical part can not be checked separately from each other and the whole parts must be checked.

Further, many of metal parts are used for the operating part and, therefore, it must be considered to insulate this operating part from both of the switching contact part and excess current detecting part which are electrical parts.

In the present invention, in view of the above mentioned points, a partition wall is integrally formed in the middle on the inside surface of the side wall of a case made of a synthetic resin to separately form upper and lower space parts which are open respectively outward, a handle operating part is arranged in the upper space part, a switching contact part and excess current detecting part are arranged in the lower space part, holes are made vertically through both sides of the partition wall, a moving plate for operatively connecting the handle operating part and switching contact part with each other is arranged in the hole on one side and an operatively connecting plate for operatively connecting the excess current detecting part and handle operating part with each other is arranged in the hole on the other side so that such defects as referred to before will be successfully solved.

An object of the present invention is, therefore, to provide a mold case circuit breaker wherein each of the said parts which are respectively made to be a unit can be arranged in an optimum state and the assembling work and maintenance service can be carried out efficiently.

Other objects and advantages of the present invention will be made clear by the following description of the invention detailed with reference to a preferred embodiment in conjunction with accompanying drawings, in which:

FIG. 1 is an explanatory view showing schematically the arrangement of a circuit breaker of the present invention;

FIG. 2 is an upper surface view of the apparatus of the present invention;

FIG. 3 is a lower surface view of the same with a back lid removed;

FIG. 4 is a side view of the same;

FIG. 5 is a view showing the interior with a part of a cover cut off;

FIG. 6 is an upper surface view shown with the cover removed;

FIG. 7 is an upper surface view in FIG. 6 shown with an upper lid removed;

FIG. 8 is a lower surface view in FIG. 3 with a lower lid removed;

FIG. 9 is a sectioned view shown along an input terminal and output terminal in FIG. 6;

FIGS. 10A through 10C are upper surface view, lower surface view and vertical sectioned view substantially at the centre of a chassis;

FIG. 11 is a cross sectional view along a carrier of the chassis;

FIG. 12 is a perspective view of an operating part;

FIG. 13A is a perspective view of the operating part as disassembled, and FIG. 13B shows main elements in the operating part;

FIG. 14A is a front view of the operating part as assembled;

FIG. 14B is a rear view of the same;

FIG. 14C is a side view of the same;

FIG. 15 is a perspective view of an electromagnet employed in the device;

FIGS. 16A through 16C show a coil in the above;

FIG. 17 is a perspective view of a switching contact unit;

FIG. 18 is a perspective view of a carrier;

FIG. 19 is a perspective view of an armature;

FIG. 20 is an elevation of a handle;

FIGS. 21 and 22 are fragmentary sectioned views for explaining the operating part as fitted;

FIGS. 23A, B and C are views for explaining the operation of the operating part;

FIGS. 24A through 24C are view for explaining the operation of the contact plate;

FIGS. 24A through 24C are fragmentary sectioned views showing operations of contacting plate; and

FIGS. 25A and 25B are explanatory views showing operative relation between certain main elements in the operating part.

FIG. 1 shall be explained in the following.

FIG. 1 shows a unit arrangement of a circuit breaker of the present invention. In the drawing, INPUT is an input terminal, OUTPUT is an output terminal and these terminals are arranged on both sides of a case A. B is a switching terminal. C is an excess current detecting part. D is an operating part. An upper space and lower space are formed by a partition wall E in the case A. The operating part D is arranged in the upper space.

The switching contact part B and excess current detecting part C are arranged in the lower space. F is an operatively connecting plate integrally having an armature for transmitting the operation of the excess current detecting part C to the operating part D. F' is a carrier for transmitting the operation of the operating part to the switching contact part. The electric current path is from the input terminal through the switching contact part B and excess current detecting part C to the output terminal OUTPUT. The operation sequence is from the excess current detecting part C through the operatively connecting plate F, operating part D and carrier F' to the switching contact part B. G is a handle. The oper-

ation sequence is from the excess current detecting part C through the operatively connecting plate F, operating part D and carrier F' to the switching contact part B. G is a handle. The oper-

ing part D is manually operated by the handle G so as to make ON and OFF.

FIG. 2 shows an upper surface view, in which 57 is a handle to be rotated so as to have three positions of U, V and W within a fan-shaped concave part 68 provided on a cover 65. The "trip" is indicated by a red mark appearing in an indicating window hole 62 made on the upper surface of the case. 70 is a set screw used to fit the cover 65 to the chassis.

FIG. 3 is a lower surface view showing the circuit breaker of the present invention with the bottom plate removed. Thin parts 69 are provided on the side wall 65a of the cover 65 so that electric wires 66 may be inserted and fitted within the unit by removing said parts. 1

15 I is a chassis, and 64 is its lower lid.

FIG. 4 shows a side view of the circuit breaker. A handle 57 is rotatably provided on the cover 65. 69 is a thin part.

FIG. 5 shows a vertically sectioned view of the above. The electric wires 66 are fitted to the chassis 1.

FIG. 6 is an upper surface view of the device in FIG. 1 shown with the cover 65 removed. 5 and 6 are respectively an input terminal and output terminal. A fan-shaped indicating plate 63 is fixed integrally with the handle 57 to the lower part of the handle 57. A trip indicating part 63a is provided on this indicating plate so that, with the rotation of the handle 57, the trip indicating part 63a will move and that, when the indicating part 63a is positioned below the indicating window hole 62 of the lid 59, the trip state will be indicated. 59b is a concave part made on the upper lid 59. 59c is an edge of the lid.

FIG. 7 is a view showing the interior of the device shown in FIG. 6 with the upper lid 59 removed.

In the drawing, the operating part D is secured between both side walls 2 of the chassis 1. There are shown a carrier F' (indicated by 22 in the drawing) operated by said operating part D and an operatively connecting plate F (indicated by 25 in the drawing) operated by the excess current detecting part C.

FIG. 8 is a view shown in FIG. 3 with the lower lid 64 removed. There are shown the excess current detecting part C, switching contact part B and operatively connecting plate F (25) operated by the excess current detecting part C.

FIG. 9 is a vertically sectioned view of the device of the present invention and is a detailed view corresponding to FIG. 1. There are shown the input terminal a 5, switching contact part B, excess current detecting part C, operatively connecting plate F, operating part D, carrier F' and output terminal b 6. The excess current detecting part C and operating part D are arranged as separated above and below the partition wall E(3) of the case.

FIGS. 10A through 10C show a chassis A(1), wherein FIG. 10A is an upper surface view thereof. The operating part D (not illustrated here) is fitted in the space between the side walls 2. 71 is a hole for fitting the operating part D. The space is sectioned into an upper space and lower space by a partition wall 3. 72 and 73 are communicating windows made in the partition wall 3. The carrier F' (not illustrated here) is inserted into the communicating window 72 and the operatively connecting plate F (not illustrated here) is inserted into the communicating window 73. FIG. 10B is a lower surface view. The communicating windows 72 and 73 are seen between the side walls 2. 74 is a parti-

tion wall for housing the elements forming the excess current detecting part C as described later. FIG. 10C shows a vertically sectioned view of the chassis. There are shown the partition wall 3 and communicating windows 72 and 73.

FIG. 11 is a sectioned view of the device along the communicating window 72, wherein the carrier 22 (or F') is shown here.

Now the formation of each part shall be detailed.

FIG. 12 shows an operating part unit. FIG. 13A shows the respective elements thereof as disassembled in a perspective view. The above described operating part D is held between two ground plates 33 and 33'. 39 is an arcuate groove made in the ground plates. 75 is a hole made in each ground plate, in which the long leg 37a of a later described U-shaped shaft 37 is pivoted. Said U-shaped shaft 37 has a long leg 37a and short leg 37b. In an operating plate 38 formed to be U-shaped by bending two plates, there are formed two holed 38a and 38b and a calked pin 38c inside. The long leg 37a of the shaft 37 is inserted through the hole 38a of the operating piece 38 and is inserted into the hole 75 of the ground plate 33. The short leg 37b is inserted into the hole 38b of the operating piece through a roller 76 contained inside the operating piece 38 (see FIG. 12). That is, the operating piece 38 is fitted to the ground plates 33 and 33' so as to be rotatable with the shaft 37a as a center. 40 is a turning arm provided with a tip part 40a as somewhat inclined at one end, with a hole 40c at the other end and with a projection 40b in the substantially intermediate part. A shaft 41 is inserted in the hole 40c of the turning arm 40. Further, the turning arm 40 is inserted in the intermediate part (between the hole 40c and projection 40b) into the intermediate part (between the hole 38b and pin 38c) of the operating plate 38 (see FIG. 12B). 42 is a hanging frame bent to be a U-shaped. 42a is its connecting part. 42b is a pivoting hole. The hanging frame 42 has at its tip engaging parts 44 with which the shaft 41 of the turning arm 40 is to be engaged and inclined parts 45. The ground plates 33 and 33' are combined with each other with a fixed space between them by inserting the projections at both ends of calked rivets 34 into the holes 33a and 33'a. The operating plate 38 is rotatably supported between both ground plates with the long leg 37a of the U-shaped shaft 37 inserted in the holes 75 of the ground plates 33 and 33'. The hanging frame 42 is rotatably supported by the ground plates with a shaft 43 inserted in the hole 42b of the hanging frame and the holes 33b and 33'b of the ground plates. 49 is a responding piece formed to be substantially L-shaped and having a bent part 49b formed at one end, a pivoting hole 49c formed at the other end and a projection 52 formed on the side opposite the bent part 49b. The responding piece 49 is rotatably supported between the ground plates 33 and 33' by inserting a shaft 50 in the hole 49c of the responding piece 49 and the respective holes 33c and 33'c of the ground plates 33 and 33'.

The above mentioned responding piece, hanging frame and turning arm are so arranged that, as shown in FIG. 13B, the tip parts 49a and 52 of the responding piece 49 will be engageable with the bent part 42a of the hanging frame 42 and the shaft 41 inserted in the hole 40c of the turning arm 40 will be contactable with the engaging part 44 and inclined part 45 of the hanging frame 42. A spring 51 is inserted between the projection 54 of the responding piece 49 and the bent pro-

jection 53 of the ground plate 33 so as to give a counter-clockwise pressing force to the responding piece 49. A spring 56 is engaged at one end with the short leg 37b of the U-shaped shaft 37 and at the other end with the hole 33d of the ground plate 33 so as to give a clockwise torque to the operating plate 38. 46 is a U-shaped spring inserted at the open end 46b in the holes 48 of the ground plates 33 and 33', engaged in the intermediate part 46a with the cut and raised parts 47 of the ground plates 33 and 33' and contacted at the other end 46c with the sides 44d of the engaging parts 44 so as to give a clockwise torque to the engaging parts 44. The thus formed state is shown in FIGS. 14A through 14C, in which FIG. 14A shows a front view of the operating part, FIG. 14B shows its rear view and FIG. 14C shows its side view.

FIGS. 15 and 16A through 16C show an oil dash pot type electromagnetic device employed as an excess current detecting part. It is formed of a coil 17, coil frame 18, L-shaped yoke 20 and oil dash pot 20'.

FIG. 17 shows a switching contact unit, in which a movable contact 13 is provided at the tip of a contact plate 12, a hole 12a is provided in the intermediate part, a middle leg 10a of an E-shaped supporting metal piece 10 is inserted in the hole 12a, the contact plate 12 is embraced on the sides by hooked parts provided at the tips of both legs 10b and 10c and the contact plate 12 is supported rotatably on the supporting metal piece 10 by a coil spring 77 fitted on the middle leg 10a. 78 is a terminal metal piece connected with the contact plate 12 through a lead wire 15.

FIG. 18 shows the carrier 22 (or F') in which grooves 22a for inserting the contact plate 12 are made on the lower side and a stepped part 24 to contact the turning arm 40 is made on the upper side as described later.

FIG. 19 is of an operatively connecting plate to which is fixed an armature 25 formed of a turning plate 27, to the lower side of which is fixed an iron piece 26 with a pin 29 and in a part of which is provided a projection 25' to push the bent part 49b of the responding piece 49. 30 is a supporting shaft provided to project at each end of the operatively connecting plate so as to rotatably fit the plate to the chassis 1 as described later.

FIGS. 20 and 22 show the handle 57 made of a synthetic resin. 57a is a hole in which the long leg 37a of the U-shaped shaft 37 is to be inserted and which is made through the handle 57. 57b is a hole in which the short leg 37b is to be inserted and which does not pass through the surface.

Now the assembly of the device of the present invention shall be explained.

The respective leg parts 5b and 6b of the L-shaped input terminal metal piece 5 and output terminal metal piece 6 are inserted respectively in the concave parts 1a and 1b of the chassis 1 (see FIGS. 7, 8, 9 and 10) made of an insulator. Wire fastening screws 7 are fitted to the respective upper pieces 5a and 6a of the terminal metal pieces 5 and 6 and a fixed contact 9 is provided on the leg part 5b of the input terminal metal piece 5.

Then, the opening on the back surface of the chassis (FIG. 10B) is directed upward and the stepped part 24 of the carrier 22 (FIG. 18) is inserted in the communicating window 72 of the chassis 1, then the supporting metal piece 10 (FIG. 17) of the contact plate 12 is inserted in the concave part 1d (FIG. 10B) of the chassis and the metal piece 78 is inserted in the groove 1e of the chassis to fit the contact plate. Then the coil frame

18 of the electromagnet (FIGS. 15 and 16) is inserted between the wall parts 1f and 1g of the chassis to fit the electromagnet, and the coil 17 is soldered in the end part 17a to the metal pieces 78 and 66. Then the back lid 64 is secured to the bottom surface of the chassis.

Thus the assembly of the electric parts through the opening on the back surface of the chassis is completed. Then the opening on the front surface of the chassis is (FIG. 10A) is directed upward. First, the hole 71 is aligned with the hole 33 of the ground plate of the completed operating part (FIGS. 12 and 14) and the operating part is fixed to the chassis with the rivet 36 (FIG. 21). Then the operatively connecting plate 25 is fitted. The indicating plate 63 indicating the trip is fitted to the U-shaped shaft 37, then the upper lid 59 is secured to the upper surface of the chassis 1, the long legs 37a and 37b of the U-shaped shaft 37 are inserted respectively in the holes 57a and 57b (FIG. 20) of the handle 57, a lock washer 57b is fitted to the upper part 20 of the long leg 37a, a lid 79 is fixed above the long leg 37a (FIG. 22) and a case 65 is applied (FIGS. 3 and 4).

Now the operation of the device according to the present invention shall be described in the following.

i. FIG. 23A shows the contact in the OFF-state in which the contact plate 12 is separated from the fixed contact 9 (see FIG. 24A). In this case, the handle 57 is in the position of W in FIG. 2 and the indicating plate 63 is in the position of W in FIG. 6. In this case, the projection 52 of the responding piece 49 is engaged with the end part 42b of the hanging frame 42 and the shaft 41 of the turning arm 40 is positioned at the left end of the arcuate groove 39 of the ground plates 33 and 33' and is engaged with the inclined part 44b of the hanging frame 42.

ii. When the handle 57 is rotated counterclockwise so as to be in the state shown in FIG. 23B (the handle position is in the state of U in FIG. 2), the handle will rotate with the shaft 37a as a center, the operating plate 38 will also rotate together with the handle, and the upper end part 40a of the turning arm 40 will rotate clockwise with the shaft 41 as a center. Therefore, the carrier 22 will move rightward against the resiliency of the spring 14 and, at the same time, the contact will move toward ON against the resiliency of the spring. At this time, in case the roller (of the roller bearing) slides while under the reaction on the projection provided on the turning arm and passes the apex of the projection, the displacement of the operating plate will become maximum. When the U-shaped arm 37 further rotates and the roller lowers down the slope of the projection, the carrier 22 will somewhat return to the OFF side. In this state, the spring 56 to return the handle will give a force to move the turning arm to the OFF side but, by overcoming it, a stable state will be made and the ON state will be obtained, because a dead point is formed at the projection 4b of the turning arm.

iii. If an excess current flows in this state (see FIG. 9), the attracting iron core 19 of the electromagnet will attract the armature 25 and the contact will be OFF so as to be in the trip state. Its details are as follows.

Now, by the resiliency of the spring 14, the carrier 22 will be pushed toward OFF side and this force will give a clockwise torque component to the slope 44b of the hanging frame 42 through the turning arm and to the hanging frame 42 through the shaft 41 of the turning arm and will give a torque. When the responding piece 49 and the frame are disengaged from each other, the

hanging frame 42 will escape clockwise and will be disengaged from the turning arm 40 and the shaft 41 of the turning arm will move counterclockwise with the contact point of the roller and turning arm 40 as a rotation center along the groove 39. Therefore, the carrier 22 will move to the OFF side due to the resiliency of the spring 14 and the contact will be in the OFF state. At this time, a counterclockwise force (toward OFF) will be given to the operating piece 38 by the handle spring 56 through the U-shaped shaft and the operating piece 38 will rotate. However, so that the handle may be fixed in a substantially intermediate position of ON and OFF by the positional relations of the movements of the carrier and turning arm with the calking pin of the operating piece, their displacements are set. At this time, the red mark of the indicating plate 63 will appear in the indicating window 62 of the indicating plate 63 to show the trip state. The handle position will be the position of V in FIG. 2. A red mark of 63a will appear in the window 62 in FIG. 6.

In the operation of this trip, even if the handle is fixed at ON, that is, even if the state that the operating piece 38 remains fixed in the state of ON is made by an external force, the contact will be separated by the above described operation. That is to say, such structure is made a trip-free structure.

iv. In order that the device in this trip state may be reset to return to the original OFF state, the U-shaped shaft 37 is rotated clockwise through the handle and a twisting force is given to rotate the turning arm 40 clockwise through the pin of the operating piece 38 and the roller.

The carrier 22 moved most to the OFF side in the trip state will be moved somewhat to the ON side.

That is to say, as the force of the spring 14 to push the carrier 22 to the OFF side is set to be larger than the force of the handle spring to push the carrier to the On side through the turning arm 40 in the trip state, in this trip state, the carrier 22 will stop when it has moved most to the OFF side. When an external force is applied by the resetting operation through the handle which has been in a stable state in the intermediate position of ON - OFF, this stable point will be broken, the shaft 41 of the turning arm 40 will move along the groove 39, will be engaged again with the hanging frame 42 and will be shifted to the OFF state. Here, the explanation of one cycle of the operation ends. However, the structure for the smooth engagement of the shaft 41 of the turning arm 40 with the hanging frame 42 shall be additionally explained as follows.

In order that the hanging frame 42 and the responding piece 49 will be engaged with each other by moving the shaft 41 of the turning arm 40, as shown in FIG. 25B, the slope 44b of the hanging frame 42 if formed to be a slope denoted by a line d—d in FIG. 25A having such angle that the component by the twisting force of the shaft 41 may act to rotate the hanging frame 42 clockwise.

Further, in order to prevent the fact that, in the case of putting the shaft 41 of the turning arm 40 into the hanging frame 42, the turning arm will produce more or less deviation in the direction vertical to the plane in the rotating direction and the smooth engagement of the shaft 41 with the hanging frame 42 will be prevented, the intersecting angle of the turning arm 40 and operating piece 38 is made more parallel and the turning arm is supported by the more operating piece sur-

faces so that the deviation in the vertical direction of the turning arm will be prevented.

Now the operation of the contact plate shall be detailed.

5 FIG. 24A shows the contact in the OFF-state in
which the contact plate 12 is resiliently pressed in the
middle with a spring 14 in such direction that the mov-
able contact 13 will separate from the fixed contact 9.
Therefore, the contact plate 12 is borne at the base end
10 12a by the hooked part 1h of the chassis 1 and at the tip
by the carrier 22 so that the fulcrum of the contact
plate 12 will be at the base end 12a. The initial state in
which the carrier 22 has moved from the above state
until the contacts 9 and 13 are in contact with each
15 other is shown in FIG. 24B.

In the state in FIG. 24B, the contacts 9 and 13 are in contact with each other and the contact plate 12 is still borne at the base end 12a by the hooked part 1h.

20 The carrier 22 as further moved is shown in FIG. 24C. The carrier 22 pulls the contact plate 12 in such direction that the movable contact 13 will contact the fixed contact 9. By this pulling, the contact plate 12 will separate at the base end 12a from the hooked part 1h and the fulcrum of this contact plate 12 will be at the 25 point of contact with the carrier 22. Therefore, the spring 14 will resiliently press the contact plate 12 at the base end 12a and the movable contact 13 will be resiliently pressed in the direction of contacting the fixed contact 9. That is, the spring 14 acts to press the 30 contacts 13 into contact with the contact 9 in FIG. 24C, acts in the direction of separating the contact 13 in FIG. 24A and is thus used for both pressing and separating the contact.

35 The features of the present invention are summarized as follows:

i. As each part is made a unit, the device is simple to manufacture and adjust.

ii. As each unit is inserted or fitted in the chassis to assemble the device, the device can be efficiently assembled.

iii. As a partition wall is provided within the chassis, the part to be mechanically operated is contained in the upper space and the electric part is contained in the lower space, a design of the circuit breaker which is safe in the electric insulation is possible.

iv. As the trip state is indicated by the indicating plate through the indicating window, it is easy to recognize the state.

50 What is claimed is:

50 1. A circuit breaker comprising an input terminal part, a switching contact part electrically connected with said input terminal part, an excess current detecting part electrically connected with said switching contact part, an output terminal part electrically connected with said excess current detecting part, an operating part for operating said switching contact part in response to an electric output of said excess current detecting part, means for converting said electric output of the excess current detecting part into a mechanical motion to transmit said motion to said operating part, means for transmitting motions of the operating part to the switching contact part, and a chassis made of an electrically insulative material for housing all said parts and elements.

55

60

65

65 and elements,
said housing chassis comprising a main body having
an intermediate partition wall defining on opposite
sides thereof separated first and second chambers

which are open in opposing directions with respect to said partition wall, said partition wall being provided with a pair of small apertures to permit communication between said first and second chambers, and lid members for closing the opening of said first and second chambers,

said switching contact part and excess current detecting part being housed in said first chamber and operatively fixed to one surface of said partition wall, said operating part being housed in said second chamber and operatively fixed to the other surface of the partition wall,

said converting means extending through one of said pair of apertures in the partition wall to operatively couple the excess current detecting part with the operating part, and

said transmitting means extending through the other aperture to operatively couple the operating part with the switching contact part.

2. A circuit breaker according to claim 1 wherein said partition wall of the chassis is provided at said first

chamber side with recesses adapted to receive said excess current detecting part and said switching contact part.

3. A circuit breaker according to claim 1 wherein said switching contact part is formed of at least a contact plate having a movable contact at the tip and a window in the part near the other end and an E-shaped supporting metal piece, the middle leg of said supporting metal piece is inserted in the window of said contact plate and the tip parts of both side legs of said supporting metal piece embrace said contact plate which is pressed against the embracing parts of both legs of the supporting metal piece by a spring fitted to said middle leg.

4. A circuit breaker according to claim 3 wherein a portion of said transmitting means extends into said first chamber and forms at least one opening to loosely fit therein said contact plate of the switching contact

20 part.
